(57) **CLAIM**

The ornamental design for a container having a helical grip, as shown and described.

DESCRIPTION

FIG. 1 is a perspective view of a container having a helical grip, showing our new design;

FIG. 2 is a top plan view thereof;

FIG. 3 is a left side elevation view thereof;

FIG. 4 is a front elevational side view thereof;

FIG. 5 is a right side elevational view thereof;

FIG. 6 is a rear elevational view thereof; and,

FIG. 7 is a bottom plan view thereof.

The broken lines shown in the drawings are for illustrative purposes only and form no part of the claimed design.
